I. Atkins,
Bag Lock,
Patented Feb. 17, 1836.

Feb. 17, 1836 307
John Atkins, of Hanover, New Hampshire
Letters Patent 9402 X

The schedule referred to in these letters patent and making part of the same containing a description in the words of the said John Atkins himself of his improvement in the mail lock bolt, for fastening mail bags, valises, &c.

To all to whom these presents shall come: Be it known that I, John Atkins of Hanover, in the County of Grafton & State of New Hampshire, doth invent a new and useful improvement in the mode of fastening mail bags, other bags, valises, & other articles to which it may be applied, by a bolt which I denominate the "mail lock bolt" and the following is a full & exact description thereof:—
The improvement consists in a bolt block, which may be extended to any required length by its hinge, be bent with the leather or other material of which the bag or other article is made. It may also be adapted to straight or curved openings. The construction will be understood by reference to the drawing hereto annexed. The drawing represent a part of one side of a small mail bag with a lock at the corner. The dotted lines on the lock (a) represent the ordinary bolt of the lock at (b), the mail lock bolt commences. It is here represented as joined to the bolt of the lock with which it is moved forward & backward by the key. It consists of a series of separate pieces (c) united by hinge (d), each piece being cut in such a form, that the middle part (e) shall serve as a short & separate bolt. These short bolts, when the whole mail lock bolt is thrown forward by the key, pass through the staples (f) which as in the common mail bag are attached to the other fold of the bag, & the bag is then locked when the mail lock is drawn back, these short bolts are withdrawn from the staples & the bag is unlocked. In the drawing the material of which the bag is made is represented as cut away in the space from (g) to (h) so as to show the bolts. In other part the course of the bolt is represented by dotted lines. The advantages to be derived from the use of the mail lock bolt are 1°: greater despatch in opening & closing mail bags. 2°: superior neatness & compactness. 3°: the security of the staples from being pressed out of place or shape by their not projecting above the surface of the

brg. 4. Tightly by which the opening is closed against dust, moisture &c
5. greater durability. What I claim as my invention & not previously known
is the aforesaid mail lock bolt that is to say, all the machinery & apparatus
described herein before & in the annexed drawing, excepting the common
lock bolt & key by which the said mail lock is opened.

(Dated & signed by me at Hanover aforesaid the 1st day of December

A.D. 1835.
